Inventor:

UNITED STATES PATENT OFFICE.

WALTER F. ASTON, OF NEW YORK, N. Y.

BUCKLE.

No. 892,925.

Specification of Letters Patent.

Patented July 7, 1908.

Application filed November 13, 1907. Serial No. 401,917.

To all whom it may concern:

Be it known that I, WALTER F. ASTON, a citizen of the United States, residing at New York city, in the county of Kings and State 5 of New York, have invented certain new and useful Improvements in Buckles, of which the following is a specification.

My invention relates to clench buckles of the rustless type and my objects are to produce a buckle which will lie flat on the web under draft, hold securely when in use and be so webbed as to protect the garments of the wearer from contact with the metal. I attain these objects in the manner illustrated 15 in the accompanying drawing in which

Figure 1 is a front view of my buckle; Fig. 2 a back view, Fig. 3 a view in section showing the web engaged therewith; and Fig. 4 a modification, in section, showing the web engaged therewith.

The front 1 may be of any desired shape or design and is provided with the cupped ears 2 and 3. The back is composed of a lever which includes a serrated gripping member 4 25 and finger piece 5 at substantially right angles to one another. The pivots 6 and 7 project from the back and engage the ears 2 and 3 on the front thereby hinging the two parts together. The front 1 may have the teeth 8 30 projecting inwardly below the line of the ears as shown in Fig. 4.

In use the web is looped around the back and sewed, the free end is then rove through the chape 9 and up on itself being carried through the space between the front and

back in a substantially straight line. On shutting the back and bringing the lever into closed position the web is clenched between the serrated edge of the gripping member 4 of the lever and the back of the front, where 40 it is securely held.

As shown in Figs. 3 and 4 the web passes through in a straight line and the buckle lies flat under draft. The metal in the back is covered by the web and does not come into 45 contact with the garments of the wearer.

If the modification shown in Fig. 4 is used any downward pull on the buckle forces the web into the teeth 8 on the front and prevents downward slipping. 50

I claim

In combination with a web, and a chape, a buckle composed of a front member and a back member spaced therefrom and formed of a lever which includes a gripping member and a finger piece, said web being looped around said back so as to inclose said gripping member and finger piece and being sewed below the lower end of said finger piece, the free end of said web being passed 55 through said chape and through said space between said back and front members and being clamped to the front by said lever. 60

In testimony whereof I have affixed my signature in presence of two witnesses.

WALTER F. ASTON.
